CUTTING MACHINE

Wilbur C. Rachels, Rock Island, Ill.

Application May 7, 1945, Serial No. 592,437

7 Claims. (Cl. 164—73)

(Granted under the act of March 3, 1883, as
amended April 30, 1928; 370 O. G. 757)

1

The invention described herein may be manufactured and used by or for the Government for governmental purposes, without the payment to me of any royalty thereon.

This invention relates to a cutting machine and more particularly to a machine for cutting sheet material that is coated with or contains a substance having adhesive properties or tendencies.

The invention contemplates and has for its principal object the provision of an improved machine especially adapted for the cutting of sheet material such as waxed paper or the like and to thereby eliminate the difficulties and hazards previously encountered in the cutting of such material. The invention is particularly adapted for the cutting of waxed paper and the preferred embodiment of the invention as will be hereinafter more fully set forth provides an efficient and safe means for performing operations that were heretofore time-consuming and relatively hazardous. Waxed paper or like material is usually furnished commercially in rolls of considerable size and it was heretofore the practice to unroll the paper, to fold it into sheets approximately the desired size, and then to cut the folded sheets with an ordinary knife. Handling of the rolls of paper became a burdensome task and the cutting of the sheets involved considerable hazard because of the use of the knives. According to the present invention the handling and cutting of waxed paper or the like is facilitated and the hazards inherent in the use of knives are eliminated or substantially minimized.

It is an important object of the invention to provide an improved machine of the type referred to in which a table or similar support is adapted to carry sheets of material and has formed therein a channel or groove in which the cutter travels so that the cutting edge thereof will not directly engage the table and further so that a space is provided between the material and the table surface for the purpose of preventing the material from adhering to the table along the line of cutting.

Another important object of the invention is to provide means for unwrapping or unrolling the sheet material or the like from the rolls in which it is furnished and to wrap the material in folded, generally flat form on a reel so that it may be cut along either or both of its folded edges into sheets of the desired size.

Another object of the invention is to provide

2

a rotary cutter that may be reciprocated on a support to cut the sheet material.

It is an important object of the invention to provide means to assist the cutting operation by supplying to the material a medium, such as a solvent, having a tendency to eliminate or minimize the adhesive characteristics of the substance contained by the material.

The invention has for another object the provision of a rotary cutter contained in a housing that is provided with means whereby the medium of the type referred to above may be supplied to the cutter and thence to the material so that the substance with which the material is coated is prevented from adhering to the cutter.

Still another object of the invention is to provide means in the form of a safety shield mounted so that it is always in protective position.

The foregoing and other objects and desirable features of the invention may be more readily understood from the following detailed description of a preferred embodiment thereof as shown in the accompanying sheets of drawings in which:

Fig. 1 is a plan view of the cutting machine;
Fig. 2 is a front elevational view of the machine shown in Fig. 1;

Fig. 3 is an enlarged, fragmentary transverse cross section taken substantially along the line 3—3 of Fig. 2, showing the means for supplying a solvent or the like to the cutter; and

Fig. 4 is an enlarged transverse sectional view taken on the line 4—4 of Fig. 2 showing the relation between the cutter and the table.

Fig. 5 is an enlarged transverse sectional view taken on line 5—5 of Fig. 2 showing the bracket supporting the movable block.

The machine constructed according to the principles of the present invention preferably includes a table or support 10 disposed at a convenient height above the floor and supported on a plurality of legs in any suitable manner. At one end thereof the table is provided with a pair of transversely spaced supports 11 providing bearings for the opposite ends of a transverse shaft 12. This shaft carries rotatably thereon a pair of coaxial spools 13 separated at their inner ends by a compression spring 14. Each spool is preferably slightly tapered and is provided at its outer end with a disk or washer 15. The shaft and spools provide means for rotatably carrying a roll of material such as waxed paper or the like. Such a roll is indicated diagrammatically in the drawings and is designated by the numeral 16.

The table 10 continues beyond the supports 11 and includes a pair of transversely spaced horizontally extending supporting portions 17, each of which has a bearing 18 for journaling a transverse shaft 19 that forms the central element of a wrapping reel, indicated generally by the numeral 20. As best shown in Fig. 1, the central element of the shaft 19 is preferably square in cross section and is provided with an axial slot 21 which receives inner reduced ends of a pair of reel members or plates 22. Axially spaced setscrews 23 are threaded into the central portion of the shaft 19 and engage the inner portions of the reel plates 22. These setscrews thus serve to mount the reel plates for adjustment radially with respect to the axis of the shaft 19 along the common diameter on which the reel plates extend. One of the plates is preferably provided at its opposite ends with guide members 24 which serve to guide the sheet material as it is transferred from the roll 16 to the reel 20. A crank 25 is keyed or otherwise secured to the end of the shaft 19 and serves as means by which the reel may be rotated in the bearings 18. Since the plates 22 occupy a common diameter extending through the axis of the shaft 19 there is provided means by which the paper may be unrolled from the roll 16 and transferred to the reel 20 in folded, generally flat form. The paper may then be cut along one or both of its folded edges; that is, along the outer edges of one or both of the reel plates 22. It will be understood of course that several wraps are made on the reel 20 so that when the material is cut as aforesaid several sheets result.

The structure just described performs a function that is preliminary to the cutting of the sheets ultimately to their desired sizes. For the purpose of completing the cutting, there is provided a second cutting means conveniently mounted in proximity to the roll-supporting structure 11-15 and the reel 20.

The table or support 10 is provided at its upper-surface with a portion adapted to support a plurality of sheets of material that may have been previously prepared or cut on the reel 20. The table is provided at longitudinally spaced points on its upper surface with a pair of upstanding brackets 26 and 27 each having spaced vertical rods 58 and 59 slidably supporting blocks 60 and 61 which carry the opposite ends of a pair of longitudinally running slide bars 28 that provide means for mounting a cutting means, indicated generally at 29. The cutting means includes a housing 30 provided with longitudinally spaced portions, 30a and 30b, each of which is formed with a pair of vertically spaced, longitudinally running bores through which the slide bars 28 extend. This arrangement serves to mount the housing 30 slidably on the bars 28 for reciprocation in a vertical plane longitudinally of the table 10. The housing 30 includes also a forwardly projecting portion 30c which contains journaled therein a transverse shaft 31 extending at opposite sides of the housing. The shaft carries at one end thereof for rotation therewith a rotary cutter 32. The blocks 60 and 61 are movable vertically with respect to the table 10 so that the slide bars, and consequently the housing and cutter 32, may be disposed at different heights above the table.

The housing 30 carries means, preferably power-operated, for driving the rotary cutter 32 through the shaft 31. In the present instance, the driving means takes the form of an air motor

5 contained in a portion 33 of the housing 30, having suitable connections to the shaft 31 to rotate the same for driving the cutter 32. The motor is supplied with air under pressure through a flexible conduit 34 which enters the housing portion 33 and the motor through a handle element 35 secured to the housing of the motor 33. The handle element includes a control 36 for regulating the flow of air to the motor 33. The combining of the handle 35 and control member 36 in the same unit provides for convenient means by which an operator may reciprocate the cutting means 29 on the slide bars 28 and at the same time control the speed of the cutter 32 by regulating the flow of air to the motor. It will be understood of course that the particular type of motor set forth has been chosen only for the purpose of illustration and as a preferred expedient in the operation of the present embodiment of the invention. This power means may be replaced with any equivalent or suitable means as desired.

10 The cutter 32 is enclosed in a housing 37 that is preferably formed of sheet metal and which provides a complete enclosure of the cutter except at the bottom peripheral edge thereof at which point the housing 37 is open so that the cutting edge of the cutter may be disposed in close proximity to the upper flat surface of the table 10. The upper portion of the housing 37 is provided 15 with a suitable material such as felt packing or the like, indicated generally at 38, through which the cutting portion of the cutter passes as it rotates. A container 39 is carried above the housing 37 and includes a connection 40 through the 20 housing 37 to the packing or wiper material 38. The container is adapted to contain a supply of a medium such as a solvent having a tendency to minimize the adhesive characteristics of the substances that coats or is contained by the material 25 to be cut. In the present instance, wherein the machine is adapted for the cutting of waxed paper, it has been found that kerosene or coal oil serves as a suitable solvent. This solvent is supplied through the conduit 40 to the packing 38 and thence to the peripheral cutting portion 30 of the cutter 32. As the cutter cuts the sheet material, the film of solvent thereon is transferred to some extent to the material so that cutting thereof is facilitated. At the same time 30 the wax or other substance, that would normally have a tendency to accumulate on the cutter because of its adhesive characteristics, is wiped off the cutter by means of the saturated packing or wiper 38.

35 The upper surface of the table 10 is provided with a longitudinal channel in which the peripheral cutting portion of the cutter travels as the cutter is reciprocated on the slide bars 28. This channel is preferably formed by a pair of parallel, 40 longitudinally running flat members 41 spaced slightly apart at their inner edges. At one end of one of the flat members 41 there is provided a transversely extending angle bar 42 rigidly secured to the upper surface of the table 10. The 45 upturned edge of the angle bar 42 and the proximate member 41 delineate a space on the surface of the table on which material may be supported preparatory to the cutting operation, the upturned edge of the angle bar 42 serving as guide means for squaring the paper.

50 The opposite side of the table 10 includes a laterally extending support 43 on which is carried a transversely running gage or measuring bar 44, preferably graduated in inches and having its inner end disposed adjacent the cutting

plane. As shown in Fig. 1, the inner end of the bar is disposed a half inch away from the cutting plane, although the first graduation on the bar is actually one inch from the cutting plane. The measuring bar is slotted longitudinally thereof as at 45 and carries for adjustment therein a gage member or block 46. This block may be positioned at any desired point in the slot 45 according to the size of the sheet to be cut.

The block 61 at one end of the table 10 has journaled therein a pulley 47 on a transverse axis. A flexible element such as a rope or the like 48 is connected at one end to the cutter-supporting housing 30, is trained over the pulley 47, and has its other end connected to a counterweight 49 preferably housed in a vertically extending tube 49. Each of the slide bars 28 carries at its end adjacent the block 61 a compression spring 50 serving to provide resilient stop means for the cutter when it is moved to one end of its stroke. An adjustable stop 51 including a compression spring 52 is mounted on one of the bars 28 at the other end thereof and serves as resilient stop means for the cutter at the other end of the stroke.

The cutter housing 37 is provided with suitable means for shielding the lower peripheral portion thereof so that the possibility that the operator may be injured is eliminated. For this purpose the housing 37 is provided with a transverse pivot pin 53 on which is mounted a swinging member having a pair of arms 54. Each arm extends downwardly along one side of the housing 37 and has pivoted to its lower end a safety shield 55 that runs parallel to the side of the housing 37. The swinging member includes a downwardly extending portion 56 abutted by one end of a compression spring 57 which has its other end abutting a lug 58 on the housing 37. The spring operates to urge the arms 54 in a clockwise direction, thus urging the safety shields 55 downwardly against the surface of the table 10. When sheets of material are passed across the longitudinally running flat members 41 on the table and the cutter is then moved over the material, the safety shields may move yieldingly upwardly, maintaining, however, their protecting relationship with respect to the cutter 32.

In the operation of the machine, a roll of material is mounted on the spindles 13 and the reel 20 is adjusted to the desired size. In a preferred use of the reel, the distance between the outer edges of the reel plates is adjusted so that this distance is one half the desired size of the sheets of material to be cut. Thus, as the reel is rotated to unroll the material from the roll 16, the material is wrapped on the reel in folded, generally flat form. The reel is rotated until a sufficient number of wraps have been taken thereon (which number will vary according to the weight of the material) and the folded material is then cut along one of its folded edges. The resulting sheets are then unfolded and laid on the surface of the table 10 bounded by the members 41 and 42 as aforesaid. In this instance several sheets, depending upon their weight, may be cut at the same time. The adjustable member 46 on the measuring bar 44 is set at the desired position and the several sheets of material are moved across the table 10 until the leading edge of the material is aligned with the block 46. By means of the operating handle and control member 36 the operator applies power to the cutter 32 and moves the cutter across the paper. This operation is repeated as often as is necessary to supply

the desired number of sheets. Because of the narrow channel provided by the closely spaced flat bars 41, the material being cut is raised slightly above the true plane of the table surface and there is thus provided a longitudinal space below the material which serves to prevent the material from adhering to the table along the line of cutting; further, since the cutter runs in this channel, the material may be cut completely and there is no possibility that the cutting edge will engage the table surface.

It will be seen from the foregoing description that the objects set forth above are efficiently and simply achieved. Undoubtedly other objects and advantages of the invention will appear to those skilled in the art. It will be understood of course that the foregoing description pertains to only a preferred embodiment of the invention and that numerous modifications and alterations may be made therein without departing from the spirit and scope of the invention as defined in the appended claims.

I claim:

1. A machine for cutting sheet material coated or impregnated with wax or like substances, comprising a cutting table, a pair of supports carried on said table in longitudinally spaced relationship and including upright portions extending above the upper surface of said table, a longitudinal slide bar carried at its opposite ends in said upright portions of said support, a housing carried by said slide bar for reciprocation thereon longitudinally of said table, said housing including means forming an opening at its under side in close proximity to the upper surface of said table, a rotary cutter journaled in said housing and disposed in a vertical longitudinal plane and extending through said opening in said housing, power means for rotating said cutter, means for reciprocating said housing on said slide bar and including a control for said power means, means including the upper surface of said table for supporting material to be cut, means forming a longitudinal channel in the upper surface of said table over which the sheet of material may be fed and into which the periphery of said cutter may run as said housing is reciprocated on said slide bar, means providing a safety shield disposed adjacent the bottom of said housing at the portion thereof through which said cutter extends, means mounting the safety shield on said housing for yielding upward movement as said housing is reciprocated over the material fed over the aforesaid channel, a guide bar on said table including means for measuring and guiding the material to be cut, and means including an inlet in said housing for supplying to said cutter a medium having a solvent action on the substance with which the material is coated or impregnated.

2. A machine for cutting sheet material coated or impregnated with wax or like substances, comprising a cutting table, a pair of supports carried on said table in longitudinally spaced relationship and including upright portions extending above the upper surface of said table, a longitudinal slide bar carried at its opposite ends in said upright portions of said support, a housing carried by said slide bar for reciprocation thereon longitudinally of said table, said housing including means forming an opening at its under side in close proximity to the upper surface of said table, a rotary cutter journaled in said housing and disposed in a vertical longitudinal plane 75 and extending through said opening in said

housing, means for rotating said cutter, means for reciprocating said housing on said slide bar, means including the upper surface of said table for supporting material to be cut, means providing a safety shield disposed adjacent the bottom of said housing at the portion thereof through which said cutter extends, and means mounting said safety shield on said housing for yielding upward movement as said housing is reciprocated over the material fed over the aforesaid channel, a guide bar on said table including means for measuring and guiding the material to be cut, and means including an inlet in said housing for supplying to said cutter a medium having a solvent action on the substance with which the material is coated or impregnated.

3. A machine for cutting sheet material coated or impregnated with wax or like substances, comprising a cutting table, a pair of supports carried on said table in longitudinally spaced relationship and including upright portions extending above the upper surface of said table, a longitudinal slide bar carried at its opposite ends in said upright portions of said support, a housing carried by said slide bar for reciprocation thereon longitudinally of said table, said housing including means forming an opening at its underside in close proximity to the upper surface of said table, a rotary cutter journaled in said housing and disposed in a vertical longitudinal plane and extending through said opening in said housing, means for rotating said cutter, means including the upper surface of said table for supporting material to be cut, means forming a longitudinal channel in the upper surface of said table over which the sheet of material may be fed and into which the periphery of said cutter may run as said housing is reciprocated on said slide bar, and a guide bar on said table including means for measuring and guiding the material to be cut.

4. A machine for cutting sheet material coated or impregnated with wax or like substances, comprising a cutting table, a pair of supports carried on said table in longitudinally spaced relationship and including upright portions extending above the upper surface of said table, a longitudinal slide bar carried at its opposite ends in said upright portions of said support, a housing carried by said slide bar for reciprocation thereon longitudinally of said table, said housing being formed with an opening at its underside in close proximity to the upper surface of said table, a rotary cutter journaled in said housing and disposed in a vertical longitudinal plane and extending through said opening in said housing, means including the upper surface of said table for supporting material to be cut, means forming a longitudinal channel in the upper surface of said table over which the sheet of material may be fed and into which the periphery of said cutter may run as said housing is reciprocated on said slide bar, means providing a safety shield disposed adjacent the bottom of said housing at the portion thereof through which said cutter extends, and means

65

mounting said safety shield on said housing for yielding upward movement as said housing is reciprocated over the material fed over the aforesaid channel.

5. A machine for cutting material coated or impregnated with wax or like substances, comprising a cutting table, a support positioned above the upper surface of said table, a cutter movably carried by said support, means including the upper surface of said table for supporting material to be cut, means forming a longitudinal channel in the upper surface of said table over which the sheet of material may be fed and into which said cutter may move in cutting the material, means providing a safety shield disposed adjacent the upper surface of said table and in shielding relation to the cutting portion of said cutter as said cutter moves to cut the material, and means mounting said safety shield for yielding upward movement upon contact with the material as the material is fed over the aforesaid channel.
6. A device for cutting sheet material, comprising a power driven knife enclosed by a reciprocably mounted housing opened at its underside; a forked rocker arm pivotally mounted on said housing at an intermediate point along its tines, the free end of each time pivotally carrying a safety shield adjacent the said open underside and spaced from the sides of said housing, the closed end of said tines having resilient connection with said housing urging said tines to maintain said shields in protective relationship with said open underside.
35. 7. A machine for cutting sheet material comprising a cutting table, a rotary cutter mounted for reciprocation above said table, a housing for said cutter reciprocable thereon and having an opening at its underside in proximity to the upper surface of said table and through which said rotary cutter extends; means providing a safety shield disposed adjacent the bottom of said housing at the portion thereof through which said cutter extends, and means mounting said safety shield on said housing for yielding upward movement as said housing is reciprocated over the material to be cut.
